SNOWPLOW

Harleigh R. Holmes, Harleigh R. Holmes, Jr., and
Lee Edgar Holmes, Littleton, Colo.

Application December 9, 1943, Serial No. 513,580

14 Claims. (Cl. 37—43)

This invention relates to improvements in snow plows of the type employed for removing snow from public highways.

In order to keep the highways open for travel during the winter, they must be cleared after each heavy snowfall. Whenever snow is accompanied by high winds so as to form a blizzard, the snow frequently drifts and packs, making it too high and hard in places to be removed by the ordinary A-type snow plow and this makes it necessary to employ a rotary snow plow of some form.

It is the object of this invention to produce a snow plow of a very simple and substantial construction that can be built either onto the front end of an ordinary truck or constructed as a part of a specially designed truck and which will have a large capacity for removing snow.

Snow plows of different types employing centrifugal fans for discharging the snow to one side or the other of the roadway, are well known. Such snow plows, however, are open to certain objections which need not be enumerated here and which the present construction avoids.

It is one of the objects of this invention to produce a snow plow having two laterally spaced wheels provided with radially extending blades which are mounted at opposite ends of an ordinary front wheel drive axle of the type shown and described in Patent No. 1,619,672, granted on March 1, 1927, and to provide said front axle and wheel construction with a steering mechanism by means of which the bladed wheels can be simultaneously and equiangularly adjusted about parallel vertical pivots, whereby the two comparatively narrow wheels will each cut a furrow greater than its own width, thereby simplifying the construction, wherefore the device can be made and sold at substantially lower price than the usual type of snow plow.

Another object of this invention is to produce a snow plow of the type described in which the snow can be delivered to either side of the roadway, as may be found most convenient and desirable.

Figure 1 is a top plan view of the improved snow plow showing the same attached to the front end of a four-wheel drive truck which has been indicated in a general way;

Figure 2 is a side elevation;

Figure 3 is a front elevation;

Figure 4 is a section taken on line 4—4, Figure 2;

Figure 5 is a partial section through the hub

of one of the bladed wheels showing the manner of attaching the guide thereto;

Figure 6 is a fragmentary diagrammatic view showing the relation of the parts;

Figure 7 is a diagram looking down on the machine showing the position of the parts during operation;

Figure 8 is a section taken on line 8—8, Figure 4;

Figure 9 is a section taken on line 9—9, Figure 2;

Figure 10 is a side elevation showing a slightly modified form of construction;

Figure 11 is a top plan view taken substantially on line 11—11, Figure 10;

Figure 12 is a diagrammatic view partially in section, showing the position of the principal parts during operation;

Figure 13 is a partial front elevation showing the appearance of the deflector plate during operation; and

Figure 14 is a diagrammatic view showing a means for adjusting the deflector plate.

In the drawings reference numeral 10 designates the side frame members of a four-wheel drive truck, whose wheels have been indicated by reference numeral 11. Transverse channels 12 connect the side members at positions spaced longitudinally thereof. The front pair of drive wheels 13 is secured to an ordinary four-wheel drive axle which has been designated by reference numeral 14. A connecting link 15 is provided for the pair and this is controlled by means of a steering wheel 16 and an ordinary steering mechanism 17 which has been indicated by dotted lines in Figure 2. Since steering mechanisms are well known, the drawings have not shown the construction in detail as this forms no part of the present invention except in so far as it is an element of the combination.

An engine 18 is carried by the truck and is positioned substantially above the rear pair of drive wheels and this engine serves to propel the truck by mechanisms well known for this purpose, the transmission of which has been shown in Figure 2 and designated by reference numeral 19. The frame of the truck is provided with a support 20 that carries the transmission 19. Engine 20 is supported between the two pairs of drive wheels and 50 is provided with an ordinary radiator 21 which is connected with the water jacket of the engine by the usual connections, including the hose 22. This engine is provided with a fan 23 driven from the engine shaft in some approved manner. 55 Since the engine is of an ordinary commercial

type it has merely been indicated in a diagrammatic manner without an attempt being made to show the several parts in detail. The crank shaft projects forwardly through the crank case 24 and is provided with a flange coupling 25, one side of which is connected with the universal 26. A torque shaft 27 extends from the universal 26 to the universal 28 as shown in Figure 1. Universal 28 is connected through a flange coupling 25a with a drive shaft that enters the housing 29, where it is provided with a bevel gear 30 that is operatively connected with a similar bevel gear 31. The two bevel gears have been indicated by full lines in Figure 2 and since this is merely an ordinary way of transmitting power at right angles, the construction has been merely indicated without an attempt being made to show the specific bearings in which the shafts rotate. Extending downwardly from the bevel gear 31 is a vertical shaft 32 that transmits power to the gear housing 33, which has been indicated by dotted lines in Figure 2 and by full lines in Figure 3. Extending from the gear housing is an axle housing comprising parts 34 and 35 shown by dotted lines in Figure 1. The axle housing encloses a shaft which has been shown in Figure 3 where it has been designated by reference numeral 36. Secured to the ends of parts 34 and 35 are hub spindles of the type employed in connection with front wheel drives an example of which is shown in Figure 1 of U. S. Patent 1,619,672, granted March 1, 1927. In order to facilitate the description, the construction of these hubs has been indicated in a rather general way in Figure 3 in which reference numerals 37 designate the two vertical spindle bearings that are positioned between the axle housing and the hub spindle 38. Surrounding the hub spindle is a wheel hub 39 that rotates about the hub spindle on roller bearings, which have been designated by reference numeral 40. Extending from the shaft is a power transmitting yoke 41 that has the shape of a wide U whose sides project in between the two concentric parts of the hub 39 and are pivotally connected with the latter by means of a gimbal ring 41a and pivots 42 that are positioned on a diameter. The gimbal ring is also pivoted to the wheel hub 39 on an axis spaced 90 degrees circumferentially from the pivot connections between the yoke 41 and the gimbal ring. The wheel hub spindle 38 can move about the vertical pivot formed by the bearings 37 and the hub spindle 39 can rotate about the hub spindle on the bearings 40. An arm 43 is integrally connected with the hub spindle 38 and extends rearwardly and to the ends of which a tie rod 44 is connected in the manner shown most clearly in Figure 5. The tie rod connects both arms 43 on the ends of the axle housing so as to interconnect them for simultaneous and equiangular movement. The tie rod 44 may be controlled by means of some suitable form of steering apparatus which has been indicated in a diagrammatic way in Figure 6 and designated by reference numeral 45. Since the wheels that are carried by the axle housing parts 34 and 35 are only adjusted at infrequent intervals and must be held positively in adjusted position, it is permissible to dispense with the steering wheel and steering post and to provide some means for clamping the tie rod in adjusted position. In any event applicants do not want to be limited in any way to the use of an ordinary steering mechanism in this particular place and whatever mechanism is employed must be either

nonreversible or so constructed that it will retain its adjustment against heavy strains.

Enclosing the hub 39 is a cylindrical sleeve 46 that is held in place and held against rotation by suitable means. In Figure 5, the sleeve 46 has been shown as secured between the outwardly extending flange 47 and the flange 48 that forms the outer periphery of the hub cap 49. Either splines or other means for preventing relative rotation between the hub 39 and the sleeve 46 must be provided. Secured to the inner end of the hub spindle 38 is an annular ring 50 of Z-shape cross section, and secured to the inner end of the hub 39 is a ring 51 of L-shape cross section. The ring 51 forms the brake drum. The brake shoes which have been designated by reference numeral 52 in Figure 3, are connected with ring 50 in some approved manner. The construction of the brake has not been shown in detail for the reason that it is merely an adaptation of the usual brake mechanism employed in front wheel drive trucks.

Extending radially from the cylindrical sleeve 46 are blades 53. These blades are slightly concave on their leading surfaces and are secured to the cylindrical sleeve by means of radially extending arms 54 from which gusset plates 55 project rearwardly so as to provide rigid braces for the blades. When the sleeves are in position, the wheels will have the appearance shown in Figure 2, when seen in side elevation, and will rotate in a clockwise direction when viewed as in Figure 2. By means of the mechanism already described, it is apparent that the bladed wheels can be rotated by power from engine 20 and that they can be adjusted angularly with respect to the longitudinal axis of the truck by some suitable adjusting means, such as that which has already been described.

Secured to the rear side of the gear housing 29 is a bracket 56 having spaced rearwardly extending arms 57 that are perforated for the reception of pivots 58. A frame comprising two side members 59, one of which is located on each side 45 of the truck, is pivotally connected with the side frames at points 60, extends forwardly and is formed with inwardly ranging portions 61 that terminate in forwardly extending bearings through which the pivots 58 extend. The two 50 side members are interconnected by a transverse channel 62 and form one link of a deformable frame construction that guides the bladed wheels. This deformable frame comprises the downwardly extending tubular housing 63 that connects the gear housing 29 with the gear housing 33, and tubular extension 64 that connects the gear housing with a runner 65 that rests on the surface 66 of the roadway. This runner will be described in greater detail hereafter. A heavy link 67 is pivoted to the rear end of the runner at 68 and extends rearwardly and upwardly and is pivotally connected with the axle housing 13 at point 69. A hydraulic cylinder 70 is pivotally connected at 71 to a stationary portion of the truck frame. 65 Within the cylinder is a piston, which has not been shown, from which the piston rod 72 extends. The lower end of this piston rod is connected with the pivot 68. A conduit 73 is connected with the interior of cylinder 70 between the lower end thereof and the piston and this conduit also extends up into the cab 74 where it is provided with a three-way valve 75 by means of which it can be connected with the intake or the outlet port of a high pressure pump 76 that is driven by the

engine 20. When oil or other liquid under high pressure is forced into the cylinder, it will move the piston upwardly whereupon the bladed wheels and the entire frame to which they are connected will be raised and can thus be supported above the surface of the ground for transportation and for any other purpose where this may be found desirable.

The runner 65 to which reference has already been made, comprises a plate 17 that forms the bottom thereof and from which plates 18 extend upwardly and inwardly and are electricwelded along their vertex 19. Projecting laterally from the edges of the bottom plate are scraper bars 20 from which curved shields 21 extend upwardly and rearwardly to a point slightly below the center of the bladed wheels.

Referring now more particularly to Figure 2, it will be seen that the shields 21 are curved on a radius somewhat greater than that of the periphery of the wheels and form a guide or backing surface against which the snow is thrown by the centrifugal action of the wheels and along which it slides upwardly.

Positioned above the curved shields are upwardly and forwardly ranging guides 22. These have a cross section substantially like that shown in Figure 9. The lower ends of the guides 22 are positioned to the rear of the upper ends of the shields 21 so that the snow will not meet any obstruction in moving from the shields to the guides. The guides have forwardly extending sides 23 that are located on the inside of the bladed wheels and are secured to the stationary brake housing 50, which forms part of the hub spindle by means of bolts 24 in the manner shown in Figure 5.

It will now be apparent that whenever the wheels are turned about their vertical pivots, the guides will also partake of a corresponding movement and they will therefore always be positioned in the plane of rotation of the bladed wheels. Any snow that is carried upwardly by the rotating bladed wheels will be given an upwardly directed movement and will be acted upon by a strong centrifugal force that keeps the snow against the surface of the shields and the guide and when it leaves the guides, it will move in the direction of arrow 25 and will be thrown to the side of the roadway in a manner that will become more apparent by a reference to Figure 7. From Figure 4 it will be seen that the bladed wheels can be turned about the vertical pivots of the hub spindles from the position in which the plane of rotation is parallel with the center line of the truck, which position has been designated by A, to an angularly related position B. The angular movement is such that the inner corner of the bladed wheel whose front end has been moved inwardly is about on a line with the center of the truck, and therefore although the adjacent surfaces of the two bladed wheels are spaced a considerable distance apart when they are in position A they will, however, clear the snow from the entire width of the roadway due to their angular position. In Figure 4 the bladed wheels have been shown as having their front ends moved upwardly but they can also be turned to a corresponding position in the opposite direction. The shields 21 are of such width that they will always cover the rear and upwardly-moving portion of the wheels in any of the positions in which they can be turned.

In the example illustrated, the width of the

truck has been taken as four feet and the bladed wheels have been selected of such size that when they are in their maximum angularly inclined position, the width of the cut will be six feet. The truck is provided with outwardly and rearwardly inclined wings or presser plates 26 that move the sides of the snow walls outwardly another two feet, and the total width of road prepared by this snow plow will therefore be eight feet. Of course by changing the dimensions and making the machine of a different size, the width of the road can be made either smaller or larger as may be found most desirable.

In Figures 10 to 14, inclusive, a slightly modified form of construction has been shown. In the embodiment already described, the shield 21 has been shown as rigidly connected with the runner in such a way that it remains stationary when the bladed wheels are turned about their vertical pivots.

In the modified construction, the shield 21a has been connected with the brake drum 50 of the hub spindle and made integral with the guide 22a. With this construction, the shield and guide always retain the same relationship to the plane of the wheel with which they are connected. Since the rotating bladed wheels are held a predetermined distance above the roadway by means of the downwardly extending tubular member 64 and the runner 65, the front edges 27 of the shields will always be kept a predetermined distance above the roadway.

Instead of connecting the hydraulic lift comprising the cylinders 10 and the piston rod 12 between the pivot 68 and the pivot 71 that is connected with the truck frame, this hydraulic lift has now been connected between pivot 28 and pivot 71a as shown in Figure 10. To provide a support for the pivot 28 two brackets 29 have been secured to the truck frame and project downwardly a sufficient distance to accommodate the hydraulic cylinder. The pivot pin 71a is connected with the links 61 and therefore when liquid under pressure is supplied to the hydraulic cylinder through pipe 73, it will raise the front ends of the links upwardly, thereby lifting the whole snow plow assembly. With this arrangement of the lifting force, the latter is practically all utilized in lifting the snow plow frame, whereas, with the arrangement shown in Figure 2 the force is separated into two components, the resultant of which is resisted by link 61.

Referring now more particularly to Figures 12 and 13, it will be seen that when the bladed wheels are turned to the right as shown in Figure 12, or in the opposite direction, the outwardly inclined wheel cuts the snow bank to a line 90 leaving a column of snow directly in front of the gear housing and the support 64. This uncut snow will pile in front of the machine and interfere with its operation unless means is provided for directing it into the blades of the outwardly inclined wheel. To remedy this difficulty, 65 a deflector blade 91 is provided. This deflector blade is secured along its front edge to a vertical shaft 92. This shaft is pivoted at its lower end in a suitable bearing in the runner and the upper end is mounted for rotation in a bearing 93 at the front end of a bracket 94 which is secured to the gear housing 29. The blade 91 must be adjusted angularly about its pivot and be held in adjusted position during operation. This adjustment may be effected by many specifically different means, but as an example of a

means that may be employed for this purpose, the upper end of shaft 92 has been provided with a worm gear 95 that is in operative engagement with a worm 96 on shaft 97. Shaft 97 has been shown as formed of two sections connected by a universal 98, the rear end has been shown as mounted in a bearing 99 that is movable about the pivot 100. A crank 101 has been shown as a means for rotating the shaft 97 and turning the vertical shaft 92.

As stated above, this adjusting mechanism has been shown merely for the purpose of illustrating a means for adjusting the deflector plate, and it is to be understood that it can be replaced by any other mechanical equivalent means and that applicants in nowise intend to limit themselves to this particular means for effecting the adjustment of the deflector plate. In the actual machine, means is provided for adjusting the deflector plate automatically whenever the bladed wheels are turned about their vertical pivots.

It will be apparent from the above description that the modification operates in substantially the same manner as the machine shown in Figures 1 to 9, inclusive. The deflector plate 91 must be provided in a machine constructed as shown in Figures 1 and 2 where the machine is to be used in connection with the removal of deep drifts of snow. For the removal of snow of moderate depth, the deflector plate may be dispensed with.

It is, of course, to be understood that the machine shown in Figures 9 to 13, is operated in the same manner as the machine already described.

Figures 10, 11, 12 and 13 are not intended to show every part, but are in some respects diagrammatic, the intention being to show clearly those parts that form the gist of this invention and to which the claims are directed.

Particular attention is called to the construction of this machine which is believed to be entirely different from anything heretofore suggested in connection with snow plows for use on public highways. The ordinary rotary snow plow has heretofore been provided with a centrifugal fan rotating about an axis parallel with the line of movement and into which the snow is directed by means of augers or by inclined side surfaces. Such snow plows have operated successfully but are of such a nature that they are expensive to construct.

With the present construction the axle which forms the support and driving means for the bladed wheels is of construction similar to the front axle of a correspondingly made front wheel drive truck and the bladed wheels are movable about vertical pivots in the same manner and by a mechanism similar to that employed for this purpose in front wheel drive trucks, except that no differential gear is required. It is evident that bladed wheels like those shown if they were rotated in planes parallel with the direction of movement, the snow would merely be thrown forwardly and would accumulate so as to render the whole machine inoperative. By the simple expedient of turning the bladed wheels about their vertical pivots to positions like those shown in Figures 4 and 7, the snow will be discharged in an annular direction and due to its high velocity it will be thrown to the outside of the roadway that is being cleared. Due to the fact that the wheels can be turned to either of two angularly related positions, either to the right as shown in Figure 7, or to the left, as shown in Figure 4, the snow can be thrown to whichever

side of the roadway is most desirable, for example if the roadway is along the side of a hill, the snow would naturally be thrown to the lower side. By providing the truck with wings or presser plates 86, the roadway can be further widened to any desired extent as even where the snow is drifted, it is never so solid that the walls cannot be moved outwardly at least two feet.

Attention is also directed to the fact that due to the direction of rotation of the bladed wheels, their rearward movement against the resistance of the snow tends to move the truck forwardly and therefore some of the power applied to the wheels to rotate them will produce a force tending to move the truck forwardly and to that extent relieve the truck propelling engine of some of its work. Tests have shown that under certain circumstances, the tractive effort exerted by the bladed wheels is sufficient to move the truck forwardly and even at times make it necessary to apply brakes.

The fact that the bladed wheels are supported from the surface by means of a runner assures that they are always a certain distance above the road surface and makes it impossible for them to gouge into the surface of the roadway. The supporting runner has been shown as provided with a slightly upwardly curved front end. It is contemplated to provide suitable means in front of this runner to prevent it from gradually rising on the snow.

Having described the invention, what is claimed as new is:

1. A snow plow comprising a truck and a transversely extending horizontal axle secured to the front of the truck, bladed wheels secured to the ends of the axle and mounted for simultaneous angular movement about vertical pivots, means for turning the wheels about their vertical pivots to effect angular adjustment, a shield extending from substantially the bottom of each bladed wheel upwardly along the rear thereof, the upper ends of the shields terminating in upwardly and forwardly inclined guides, and means for rotating the bladed wheels to move their lower surfaces rearwardly, whereby snow will be moved towards the shields and then thrown upwardly and forwardly along the guides by the centrifugal force.
2. A snow plow comprising a truck and a transversely extending horizontal axle secured to the front of the truck, bladed wheels secured to the ends of the axle and mounted for simultaneous angular movement about vertical pivots, means for turning the wheels about their vertical pivots to effect angular adjustment, a shield extending from substantially the bottom of each bladed wheel upwardly along the rear thereof, guides forming extensions of the shields, the guides being upwardly and forwardly inclined, means for rotating the bladed wheels to move their lower surfaces rearwardly, whereby snow will be moved towards the shields and then thrown upwardly and forwardly along the guides by the centrifugal force, a deflector blade positioned in front of the bladed wheel axle, mounted for angular movement about a vertical axis positioned substantially in the median plane of the truck and means for adjusting the deflector blade angularly about said pivot.
3. A snow plow comprising a truck, means for propelling and guiding the truck, a snow clearing device comprising a framework connected with the front of the truck, a transversely extending horizontal axle housing supported by the framework, a hub spindle connected to each end of the

axle housing and mounted for angular adjustment about a vertical pivot, a bladed wheel connected with each hub spindle, means for interconnecting the two hub spindles for simultaneous and substantially equal angular movements of the wheels about the hub spindle pivots, means for rotating the wheels to move their lower peripheral surfaces rearwardly, means for supporting the wheels a predetermined distance above a roadway, a curved shield secured to the last mentioned means, extending upwardly along the rear surface of each wheel, and forwardly extending and upwardly inclined guides forming continuations of said shields, said guides being secured to the hub spindles, whereby when the truck moves forwardly the rotating bladed wheels will cut the snow and move it rearwardly against the shields and thence upwardly along the forwardly inclined guides, and discharge the snow in a direction determined by the angular position of the wheels and the guides with respect to the axle housing.

4. A snow plow comprising a truck, means for propelling and guiding the truck, a snow clearing device comprising a framework connected with the front of the truck, a transversely extending horizontal axle housing supported by the framework, a hub spindle connected to each end of the axle housing and mounted for angular adjustment about a vertical pivot, a bladed wheel rotatably mounted on each hub spindle, means for interconnecting the hub spindle for simultaneous and substantially equal angular movements of the wheels about the vertical pivots, means for rotating the wheels to move their lower peripheral surfaces rearwardly, means for supporting the axle housing and the bladed wheels a predetermined distance above a roadway, curved shields extending upwardly along the rear surfaces of the wheels, forwardly extending and upwardly inclined guides forming continuations of said shields, said guides being secured to the hub spindles, whereby when the truck moves forwardly the rotating bladed wheels will cut the snow and move it rearwardly against the shields and thence upwardly along the forwardly inclined guides, whereby the snow will be projected in a direction determined by the angular position of the hub spindles and the guides with respect to the axle housing, a deflector blade positioned in front of the axle housing, mounted for angular movement about a vertical axis positioned substantially in the median plane of the truck, and means for adjusting the deflector blade angularly about said pivot.

5. A snow plow comprising a truck, means for guiding and propelling the truck, a transversely extending horizontal axle housing connected with the front end of the truck, hub spindles connected with the ends of the axle housing for movement about vertical pivots, a bladed wheel rotatably connected with each hub spindle, means for rotating said wheels in a direction to move their lower peripheral surfaces rearwardly, means for simultaneously adjusting the planes of rotation of the wheels about the hub spindle pivots, means comprising a runner for supporting the axle housing and the bladed wheels a predetermined distance above a roadway, a curved shield member attached to the runner and extending upwardly at the rear of each bladed wheel, to a point adjacent its horizontal diameter, upwardly and forwardly ranging guides secured to the hub spindles, said guides forming extensions of the shields, whereby snow cut by the bladed wheels will be

thrown rearwardly against the shields and thence against the guides and be projected forwardly and laterally at an angle determined by the angular position of the bladed wheels with respect to the direction of truck travel.

6. A snow plow comprising a truck, means for guiding and propelling the truck, a transversely extending axle housing connected with the front end of the truck, a hub spindle connected with each end of the axle housing for movement about a vertical pivot, a bladed wheel rotatably connected with each hub spindle, means for rotating said wheels in a direction to move their lower peripheral surfaces rearwardly, means for simultaneously adjusting the planes of rotation of the wheels about the spindle pivots, means comprising a runner for supporting the axle housing and the bladed wheels a predetermined distance above a roadway, curved shields attached to the runner and extending upwardly at the rear of the bladed wheels, to a point adjacent their horizontal diameters, upwardly and forwardly ranging guides secured to the hub spindles, said guides forming extensions of the shields, whereby snow cut by the bladed wheels will be thrown rearwardly against the shields and thence against the guides and be projected forwardly and laterally at an angle determined by the angular position of the hub spindles and the bladed wheels with respect to the direction of truck travel; and means comprising a hydraulic mechanism interconnecting the truck and the runner for raising the axle housing and attached parts.

7. A snow plow comprising a truck, means for propelling the truck and means for guiding it, a front wheel drive axle assembly carried by the truck and positioned to the front thereof, said axle assembly comprising an axle housing having hub spindles mounted for angular movement about vertical pivots, means for supporting said axle assembly a predetermined distance above the roadway, means for raising and lowering the axle assembly, a bladed wheel mounted for rotation on each hub spindle, means for rotating the bladed wheels comprising an engine carried by the truck, means for adjusting the hub spindles and wheels angularly about the vertical pivots, shields attached to the hub spindles extending upwardly behind the bladed wheels, guides forming extensions of the shields and having a forwardly and upwardly inclined section, whereby snow thrown against their surfaces by the action of the bladed wheels will be discharged in a direction substantially parallel with the plane of rotation of the bladed wheel.

8. A snow plow comprising a truck, means for propelling the truck and means for guiding it, a front wheel drive axle assembly carried by the truck and positioned to the front thereof, said axle assembly comprising an axle housing having a hub spindle at each end mounted for movement about a vertical pivot, means for simultaneously adjusting the hub spindles about their vertical pivots, means for supporting said axle assembly a predetermined distance above the roadway, means for raising and lowering the assembly and support, a bladed wheel rotatably connected with each hub spindle, means for rotating the wheels comprising an engine carried by the truck, guides attached to the hub spindles, said guides having portions extending downwardly at the rear of the wheel and forwardly and upwardly inclined sections, whereby snow thrown against their surfaces by the action of the bladed wheels will be discharged in a direction substantially parallel with

the planes of rotation of the bladed wheels, a deflector blade positioned in front of the bladed wheel axle, mounted for angular movement about a vertical axis positioned substantially in the median plane of the truck and means for adjusting the deflector blade angularly about said pivot.

9. A snow plow assembly for attachment to the front end of a truck, comprising an axle housing, a shaft extending through the axle housing, hub spindles connected with the ends of the axle housing and mounted for angular adjustment about vertical pivots, bladed wheels rotatably mounted on the hub spindles, means for transmitting rotation from the axle housing shaft to the wheels, a runner for engaging the roadway, a rigid member extending from the axle housing to the runner, a tubular member extending upwardly from the axle housing, a shaft in the tubular member, the lower end of the shaft being operatively connected with the shaft in the axle housing to effect a rotation thereof, a bevel gear secured to the upper end of said shaft, a drive shaft having a bevel gear operatively connected with said first mentioned bevel gear, shields positioned to the rear of the wheels and extending upwardly to a point adjacent the center of the wheel, and upwardly and forwardly inclined guides attached to the hub spindles and positioned to receive snow from the shields and direct it forwardly and upwardly in the direction of the plane of rotation.

10. A snow plow assembly for attachment to the front end of a truck, comprising an axle housing movably connected with the truck, a shaft mounted for rotation in the axle housing, a hub spindle connected with each end of the axle housing for angular movement about a vertical pivot, a bladed wheel rotatably connected with each hub spindle, a runner for engaging the roadway, a rigid member extending from the axle assembly to the runner, a tubular member extending upwardly from the axle housing, a shaft in the tubular member, means at the lower end of the last named shaft comprising cooperating gears, for transmitting rotation from the vertical shaft to the shaft in the axle housing, a bevel gear secured to the upper end of said shaft, a drive shaft having a bevel gear operatively connected with said first mentioned bevel gear, a guide positioned to the rear of each wheel and extending downwardly to a point below the center of the wheel, the upper end of the guide being upwardly and forwardly inclined, the lower end of the guide being positioned to receive snow from the bladed wheel and direct it forwardly and upwardly in the direction of the plane of rotation, a deflector blade positioned in front of the axle housing, mounted for angular movement about a vertical axis positioned substantially in the median plane of the axle housing and means for adjusting the deflector blade angularly about said pivot.

11. A snow plow comprising an automobile truck, an axle housing secured to the front end of the truck, a shaft mounted for rotation therein, hub spindles secured to the ends of the shaft for angular adjustment about vertical pivots, bladed wheels carried by the hub spindle, means for supporting said axle housing and bladed wheels a predetermined distance above a roadway, means for raising the axle housing assembly

and bladed wheels relative to the truck and the roadway, means comprising a motor carried by the truck for rotating said shaft and bladed wheels in a direction in which the upper peripheral surfaces of the wheels move forwardly, means for turning the bladed wheels about the vertical pivots to change their planes of rotation relative to the direction of truck travel, a shield and guide member carried by each hub spindle, the shield portion extending from a point underneath the bladed wheel and upwardly along its rear surface, the guides extending tangentially in an upwardly ranging forward direction, whereby snow moved rearwardly by the bladed wheels will be thrown against the shields and projected in a forward direction by the guides, a deflector plate positioned in front of the axle housing, said plate being movable angularly about a vertical pivot, and means for adjusting said plate and for holding it in adjusted position.

12. A snow plow comprising an automobile truck having a frame, and a front axle housing, a link pivoted to the truck frame and extending forwardly therefrom, a snow plow axle housing assembly pivotally attached at its upper end to the front end of the link, bladed wheels connected with the ends of said axle assembly for angular adjustment about vertical pivots, means for simultaneously adjusting the wheels about the pivots, means for rotating the wheels in a direction to move their lower surface rearwardly, a support extending downwardly from the said axle assembly, the lower end of said support forming a runner, a second link having its front end pivotally connected with the rear end of the runner, the rear end being pivoted to the front axle housing of the truck, means comprising a hydraulic cylinder and piston operatively connected with said last named link and with the truck frame for raising the snow plow axle housing assembly and attached parts relative to the truck frame, a deflector plate extending rearwardly from and swingable about a pivot extending vertically from the front end of the runner, and means for angularly adjusting the plate about the pivot and for holding it in adjusted position.

13. A snow plow comprising a front wheel drive axle assembly, a wheel hub spindle secured to each end thereof and mounted for angular adjustment about vertical pivots, means for adjusting the two hubs angularly about the vertical pivots, cylindrical sleeves removably secured to the hub spindles, the sleeves having a plurality of blades projecting radially therefrom, and means for rotating the bladed sleeves.

14. A snow plow comprising a front wheel drive axle assembly having an axle housing, a hub spindle mounted on each end of the housing for movement about a vertical pivot, a hub rotatably mounted on each spindle, a bladed wheel removably connected with each hub and a combined curved shield and guide connected with each hub spindle, the shields having curved portions positioned to the rear of the wheels and terminating in forwardly and upwardly inclined guides.
